US00D439047S

(12) **United States Design Patent** (10) Patent No.: **US D439,047 S**
Holland et al. (45) Date of Patent: ** *Mar. 20, 2001

(54) **ARTICLE CARRIER**

(75) Inventors: **Matthew J. Holland**, Baltimore; **Brian N. Kagen**, Owings Mills, both of MD (US)

(73) Assignee: **Black & Decker Inc.**, Newark, DE (US)

(*) Notice: This patent is subject to a terminal disclaimer.

(**) Term: **14 Years**

(21) Appl. No.: **29/108,894**

(22) Filed: **Aug. 5, 1999**

(57) **CLAIM**

The ornamental design for an article carrier, as shown and described.

DESCRIPTION

FIG. 1 is a front exterior perspective view of an article carrier, in accordance with the ornamental design, illustrated in its closed configuration;

FIG. 2 is a rear exterior perspective view thereof;

FIG. 3 is a front view thereof;

FIG. 4 is a rear view thereof;

FIG. 5 is a top view thereof;

FIG. 6 is a bottom view thereof;

FIG. 7 is a side view thereof; and

FIG. 8 is a front perspective view similar to that of FIG. 1, but with the article carrier illustrated in its open configuration;

FIG. 9 is a front exterior perspective view of an alternate embodiment of an article carrier, in accordance with the ornamental design, illustrated in its closed configuration;

FIG. 10 is a rear exterior perspective view thereof;

FIG. 11 is a front view thereof;

FIG. 12 is a rear view thereof;

FIG. 13 is a top view thereof;

FIG. 14 is a bottom view thereof;

FIG. 15 is a side view thereof; and,

FIG. 16 is a front perspective view similar to that of FIG. 9, but with the alternate article carrier illustrated in its open configuration.
